UNITED STATES PATENT OFFICE

ADOLPH O. SCHAEFFER, OF BROOKLYN, NEW YORK, ASSIGNOR TO ATLANTIC SERVICE COMPANY, INC., OF BROOKLYN, NEW YORK, A CORPORATION OF NEW YORK

TOILET PASTE-TUBE COMPRESSOR

Application filed June 19, 1929. Serial No. 372,106.

My invention relates to new and useful improvements in toilet paste tube compressors, and has for an object to provide a device wherein it is only necessary to lift a small handle to make it possible to insert the rear end of the toilet paste tube, and then swing the handle downwardly to lock the same in position after which, by turning a small knurled nut, the paste can be ejected from the tube in a uniform and even manner.

In a like manner, to remove a fully compressed tube, it is merely necessary to swing the handle upwardly and supply a new tube.

Still another object of the invention is to provide a toilet paste tube compressor of but few parts, some of which parts may be stamped out in great quantities after the proper dies are made while other parts may be bought from stock, thus necessitating but little machine work in the manufacture of the article.

Still another object of the invention is to provide a toilet paste tube compressor, the frame of which may be stamped out from blank metal and bent to shape while the other parts may be quickly assembled to thus provide a device that is extremely cheap to manufacture and may be sold at a relatively low price.

Still another object of the invention is to provide a relatively small paste tube compressor that is so arranged that it may be quickly taken apart and new rollers or other parts substituted if they should become damaged in service.

With these and other objects in view, the invention consists in certain new and novel arrangements and combination of parts, as will be hereinafter more fully described and pointed out in the claims.

Referring now to the drawings showing a preferred embodiment,

Fig. 1 is a front elevation with the knurled nut broken away for the sake of clearness; Fig. 2 is a side elevation of the toilet paste tube compressor and as it will appear when fastened to a wall, the dotted lines showing the tube in operative position and partly compressed;

Fig. 3 is a bottom view of the same;

Fig. 4 is a perspective of the handle and frame;

Fig. 5 is a view showing the manner in which the blank is formed before being bent in shape to form the frame; and

Fig. 6 is a sectional view taken on the line 6—6 of Fig. 1 showing the rollers in their separated position.

Referring now more particularly to the several views and first to Fig. 5, there is seen the blank 1 which may be stamped out from any desirable metal, such as brass or tin, and be nickelized, if so desired.

It will be noticed that this blank, as first formed, consists of an oblong piece with the small upwardly projecting tongue 2 and the opposite recess 3, and it will be understood that the metal taken forming the tongue 2 of one blank will form the recess 3 of the succeeding blank, so that there will be no wasted metal.

To the right of this blanked metal, there will be seen the tongue 4 which is provided with the small recess 5, this recess 5 forming a bearing for the small worm shaft 36 that will be mentioned shortly.

Glancing at Fig. 4 for the moment, it will be seen that the blank is bent at the lines 6 and 7 to thus form the two side wings or frames 8 and 9 while the central portion of the blank forms the rear wall 10 of the frame.

Now, in the side wall 8, there will be seen a small hole 11 and the slot 12, and it will also be noticed that a portion of metal 13 is forced downwardly to form a hook 14, which may be seen in Fig. 1. In a like manner, the wing 9 is provided with a hole 15, slot 16 and a small integral hook 17.

These two hooks 14 and 17 are to hang the tooth brushes on, so that they will be conveniently near the tooth paste.

Referring now for the moment to Figs. 1 and 2, there may be seen a base plate 18, which may be of metal, bakelite, hard rubber, or any other desirable material and the same may be screwed to the wall, as shown in Fig. 2, or might be cemented in a tile bathroom, if desired. This base plate 18 is provided with a recess 19 over which the tongue 2 of the

frame will fit after the tongue has been bent to shape, as shown in Fig. 4.

Beneath this recess and on the base is a raised lug 20, which will engage against the walls of the recess 3 when the frame is placed on the base, as will be readily understood.

Within this frame 1, there are two rollers, the one being a driven or idle roller 21 and the other a driving roller 22. Taking up first the driven or idle roller 21, it will be seen, from Figs. 1 and 2, that after the roller is placed in position, the small screws 23 and 24 are passed through the ends 25 of the arms 26 of a handle 27, this handle having a front cross bar 28 formed integral with the arms and also having the small lip 29. These two small screws 23 and 24, after being passed through the rear ends 25 of the handle, also pass through the respective slots 12 and 16 of the frame where they thread into the roller, so that when the handle 27 is swung upwardly, the driven or idle roller may move rearwardly in the bearing slots 12 and 16.

The driving roller 22 has the small threaded trunnions 30 which are adapted to pass respectively through the holes 11 and 15. These trunnions have a slotted head, are removable and, of course, when in place, lock the roller within the frame. These little trunnions also act as locking pins for the handle carrying the driven or idle roller as, when the handle 27 is swung forwardly and downwardly, as shown in Fig. 2, the trunnions will fit in two slots 31 and 32, thus holding the driven or idle roller in its forward position and in close proximity to the driving roller. In other words, the handle functions as a cam so as to pull the two rollers into close proximity and place the gears in their meshing position or to throw them apart. Furthermore, by having the handle formed as shown, when it is in its lower position, it slips over the two forward ends of the wings to thus brace the entire structure.

The roller 21 is provided with a small gear 33 while the roller 22 is provided with a small gear 34.

Now, at all times meshing with the gear of the driving roller 22 is a worm 35 that is formed on the driving shaft 36. Referring now particularly to Fig. 6, this operating or driving shaft 36 has its rear end mounted in an opening 37 in the rear of the frame 10 while the shaft near its front end is reduced, as indicated at 40, so that it may pass within the slot 5 formed in the tongue 4 and be held against accidental displacement.

The operation of the device is as follows: Supposing a new tube is to be placed in position, the handle 27 will be lifted by grasping the lug 29 and then thrown upwardly. This movement will cause the driven or idle roller 21 carried by the handle to move back in its bearing slots and the lower end

of a collapsible tube A may then be placed up between the two rollers.

The handle will then be moved downwardly and the roller and the handle will be moved forwardly until the two small gears 33 and 34 are in mesh. The handle will be finally forced downwardly until the slots 31 and 32 will engage the little trunnions on the forward roller, thus tightly locking the rollers and the gears together.

The end of the shaft 36 may have the integral knurled nut 38 thereon, and now to compress the tube, it will only be necessary to give the knurled nut 38 a couple of turns which, through the action of the worm, will drive the two interlocked gears, turn the rollers and thus compress the tube.

After the tube has been finally compressed, it takes but a moment to throw back the handle which will move the driven or idle roller from the driving roller and the old tube may now be removed and a new one quickly inserted. The handle will be forced downwardly again to thus lock the gears in mesh and pull the rollers into close proximity, when the device is again ready for use.

The rollers may be bought from stock and likewise the little gears, so that but little work is necessary to assemble them.

In the same manner, the worm and the shaft may be an integral piece, and should the worm shaft become damaged, it will be only necessary to remove the little threaded trunnions and the worm shaft may be raised and then moved laterally, and quickly removed from the frame.

From the foregoing, it will be seen that I have devised a little collapsible tube compressor that may be used for tooth paste or shaving cream and wherein the frame may be struck from blank metal with but little waste of metal, the tongue of one blank forming the recess of the other, and these tongues and recesses forming efficient means for fastening the frame to a base. In the same manner, these blanks are provided with holes and slots, so that they act as bearings for the two rollers, thus making it possible to quickly throw the two rollers out of driving connection.

It will be seen that by forming the device as hereinbefore explained, the entire article may be made at relatively small expense and may then be likewise quickly and cheaply assembled.

Finally, the device is one that should give long and efficient service, but should a part become damaged or worn, a new part may be quickly installed.

Having thus described my invention, what I claim as new and desire to secure by Letters Patent is:

1. A paste tube compressor comprising a frame, said frame having at said sides hole

openings and slot openings in alignment therewith, a roller having its axes journaled in the hole openings, a roller journaled and slideable in the slot openings, said rollers having gear wheels, a handle member pivotally connected with the axis of one of the rollers and having recesses adapted to receive the axis of the other roller, and means carried by the frame for turning one of the gear wheels.

2. A paste tube compressor comprising a frame having at opposite sides hole openings and slot openings in alignment therewith, a roller having its axis journaled in the hole openings, a second roller having its axis journaled and slideable in the slot openings, said rollers having gear wheels, a handle pivoted to the axis of that roller located in the slot openings and having recesses adapted to engage the axis of the other roller, and means journaled in the frame for turning one of the gear wheels.

3. A paste tube compressor comprising a frame having at opposite sides hole openings and slot openings in alignment therewith, said frame having a tongue portion provided with a recess, a roller having its axis journaled in the hole openings, a second roller having its axis journaled and slideable in the slot openings, said rollers having gear wheels, a handle pivoted to the axis of that roller supported in the slot openings and having recesses adapted to engage the axis of the other roller, and a shaft journaled in the recess of said tongue portion and having a worm engageable with the gear wheel of that roller which is journaled in the hole openings.

4. A paste tube compressor comprising a frame having a tongue adapted to interlock with a support, said frame having at opposite sides hole openings and slot openings in respective alignment with each other, a roller having trunnions journaled in the hole openings, a second roller having trunnions slidably mounted in the slot openings, a handle pivotally associated with the trunnions of the slideable roller and adapted to shift the said roller along said slot openings, each of said rollers having a gear, said gears interlocking when the handle is thrown to an operative position, means for turning one of said rollers to thereby cause the other roller to turn when the gears of the two rollers are interlocked, and the handle locking over the frame and the axes of one of the rollers when in its operable position to thereby hold the said gears in interlocked position.

In testimony whereof I affix my signature.

ADOLPH O. SCHAEFER.
